UNITED STATES PATENT OFFICE.

GEORGE MURRAY, OF BAYVILLE, NEW YORK, ASSIGNOR TO CLAUDIUS WANSOR, OF HEMPSTEAD, LONG ISLAND, NEW YORK.

WALL PLUG.

Application filed December 13, 1922. Serial No. 606,652.

To all whom it may concern:

Be it known that I, GEORGE MURRAY, of Bayville, Long Island, in the county of Nassau and State of New York, a citizen of 5 the United States, have invented certain new and useful Improvements in Wall Plugs, of which the following is a specification.

This invention is a wall plug and is intended more particularly for use in walls 10 built of hollow tile.

The object of the invention is to provide a simple and cheap plug which may be easily fitted in the wall and which will be 15 securely held to provide a firm anchor to which may be secured any parts which are to be fastened to the tile, such as door or window frames, furring for inside walls, partitions, etc. The invention is illustrated 20 in the accompanying drawing and will be hereinafter fully set forth.

In the drawing, Fig. 1 is an elevation of my improved plug in position in a tile, the tile being shown in section.

25 Fig. 2 is a perspective view of the inner or foot member of the plug.

Fig. 3 is a similar view of the outer or head member of the plug.

A portion of a hollow building tile is 30 shown in Fig. 1, said tile being of the well-known construction and comprising an outer rectangular shell 1 and one or more internal webs or partitions 2 disposed parallel with the sides of the shell.

35 My improved plug is constructed of wood and comprises a base or foot member 3 which is reenforced against splitting at one end in any convenient manner, as by securing a band of metal 4 around the same. The 40 base member may, of course, be of any desired dimensions so that all needs may be met, and it is slotted from the end opposite the band longitudinally, as at 5, to form three or more tongues 6 which are 45 tapered toward their free ends so that they will exert a wedging action when in use, as will presently appear. The outer or head member 7 of the plug is also a wooden block of elongated form having a central 50 longitudinal split or kerf 8 therein and having its sides tapered for the length of the kerf or split toward the open end thereof, as at 9, thereby forming tongues 10 adapted to fit between and cooperate with the 55 tongues 6.

In using the plug, a hole 11 is broken in the shell of the tile and the base member of the plug is inserted through the opening until its reenforced butt end bears against the internal web or partition of the tile. The outer or head member of the plug is then placed in position with its tongues 10 engaging between the tongues and it is driven home by a few light blows upon its projecting solid end. The length of the base member is about equal to the distance from the web or partition 2 of the tile to the outer surface of the shell so that the free ends of the tongues 6 will rest in the opening 11 as clearly shown in Fig. 1. 60 When the outer member is driven home, the tapered formation of the several tongues will cause them to exert a wedging action on each other so that the free ends of the outer tongues 6 will be bound firmly in 65 engagement with the rough walls of the opening 11 and the several tongues will be wedged together so firmly that it is practically impossible to pull out the plug without breaking the tile. The end of the head member of the plug will project from the tile so that it can be cut at any desired 70 distance from the latter and will furnish a firm anchor to which furring or other elements may be nailed. 75

Having thus fully described my invention, what I claim as new and desire to secure by Letters Patent of the United States is:—

1. A wall plug consisting of a base member having a reenforced butt end and a plurality of tapered tongues projecting from said end adapted to be inserted through an opening in the side of a hollow building tile with its butt end bearing against the inner web of the tile and the free ends of the tongues resting in the opening in the tile, and a base member having a plurality of tapered tongues constructed to engage and be held by the base member and effect 90 binding engagement between the base member and the tile. 95

2. A wall plug consisting of a base member having a reenforced end and longitudinal tongues extending therefrom, said 105 tongues being tapered toward their free ends, and a head member having a solid end and tapered tongues projecting therefrom, the tongues on one member being adapted to engage in the spaces between the 110

tongues on the other member whereby to bind the members together and in a hole in a wall.

3. A wall plug comprising a base member having a reenforced end and spaced tongues extending longitudinally therefrom, said tongues being tapered toward their free ends, and a head member having a solid end and a plurality of tapered tongues projecting therefrom arranged to be forced with a wedging engagement into the spaces between the tongues of the base member.

4. A wall plug comprising a base member having a butt end arranged to form an end bearing, and a plurality of spaced 15 tapered tongues projecting longitudinally from said butt end and a head member having a plurality of tapered tongues arranged to be driven in wedging engagement between the tongues of the base member. 20

In testimony whereof I hereunto affix my signature.

GEORGE MURRAY.
